[57] CLAIM

I claim the ornamental design for a safety compass, as shown and described.

DESCRIPTION

FIG. 1 is an isometric view of a safety compass; FIG. 2 is a front view of the safety compass shown in FIG. 1; FIG. 3 is a rear view of the safety compass shown in FIG. 1; FIG. 4 is a left side view of the safety compass shown in FIG. 1; FIG. 5 is a right side view of the safety compass shown in FIG. 1; FIG. 6 is a top view of the safety compass shown in FIG. 1; FIG. 7 is a bottom view of the safety compass shown in FIG. 1; FIG. 8 is an isometric view of a second embodiment of a safety compass; FIG. 9 is a front view of the safety compass shown in FIG. 8; FIG. 10 is a rear view of the safety compass shown in FIG. 8; FIG. 11 is a left side view of the safety compass shown in FIG. 8; FIG. 12 is a right side view of the safety compass shown in FIG. 8; FIG. 13 is a bottom view of the safety compass shown in FIG. 8; FIG. 14 is an isometric view of a third embodiment of a safety compass; FIG. 15 is a front view of the safety compass shown in FIG. 14; FIG. 16 is a rear view of the safety compass shown in FIG. 14; FIG. 17 is a left side view of the safety compass shown in FIG. 14; FIG. 18 is a right side view of the safety compass shown in FIG. 14; and, FIG. 19 is a bottom view of the safety compass shown in FIG. 14. The broken lines showing portions of the safety compass and marking implement in FIGS. 1-19 are for illustrative purposes only and form no part of the claimed design.
